US00D719824S

(12) **United States Design Patent**
Wagner

(10) **Patent No.:** **US D719,824 S**
(45) **Date of Patent:** **** Dec. 23, 2014**

(54) **CONTAINER**

(71) Applicant: **Graphic Packaging International, Inc.**,
Marietta, GA (US)

(72) Inventor: **Todd Wagner**, Medina, OH (US)

(73) Assignee: **Graphic Packaging International, Inc.**,
Atlanta, GA (US)

(**) Term: **14 Years**

(21) Appl. No.: **29/436,551**

(22) Filed: **Nov. 7, 2012**

(51) LOC (10) Cl. **09-03**

(52) U.S. Cl.

USPC **D9/430**

(57) **CLAIM**

The ornamental design for a container, as shown and described.

DESCRIPTION

FIG. 1 is a perspective view of a container showing my new design.

FIG. 2 is a left elevation view of the container of FIG. 1.

FIG. 3 is a right elevation view of the container of FIG. 1.

FIG. 4 is a rear elevation view of the container of FIG. 1.

FIG. 5 is a front elevation view of the container of FIG. 1.

FIG. 6 is a top plan view of the container of FIG. 1; and,

FIG. 7 is a bottom plan view of the container of FIG. 1.

The broken lines shown in the drawings depict environmental features that form no part of the claimed design.

1 Claim, 7 Drawing Sheets
